UNITED STATES PATENT OFFICE.

JAMES L. WILBER, OF FARMINGTON, MICHIGAN.

STOVE-PIPE THIMBLE.

SPECIFICATION forming part of Letters Patent No. 307,887, dated November 11, 1884.

Application filed February 23, 1884. (No model.)

To all whom it may concern:

Be it known that I, JAMES L. WILBER, of Farmington, in the county of Oakland and State of Michigan, have invented new and useful Improvements in Stove-Pipe Thimbles; and I do hereby declare that the following is a full, clear, and exact description thereof, reference being had to the accompanying drawings, which form a part of this specification.

10 This invention relates to certain new and useful improvements in the construction of stove-pipe thimbles of that class which are designed to be placed in floors and ceilings.

15 The invention consists in the peculiar manner of securing the bands to the heads, by means of which no soldering is required; also in the means employed to secure the parts together so that one band attached to one of the heads may be detached from the other 20 head to which the other band is attached, the more readily to get at and clean the interior when necessary; also, in the peculiar construction of the parts and their combination, as more fully hereinafter described.

25 Figure 1 shows the two bands and heads detached and in perspective elevation. Fig. 2 is a section showing the manner in which the bands are secured each to its head. Fig. 3 is another section showing the manner in 30 which the two parts are detachably secured together, each part consisting of a head and band.

35 In the accompanying drawings, which form a part of this specification, A represents one head, and B represents the outside shell or band. This band is preferably made of tin, and of any desired length to suit circumstances. The head A is preferably made of cast-iron with two series of holes in a larger 40 and smaller circle, as shown, the two series of such holes being separated by a ring, a, and the outside circumference of the head being another ring, b. The outside band, B, is a little smaller in circumference than the 45 outer circumference of the ring b, which rests on the end of the band, and is secured thereto by means of the metallic straps c, which embrace the ring b or a portion thereof, and the free ends of these straps pass along the 50 outer and inner wall of the band, and are secured thereto by rivet or rivets d, passing through the straps and wall of the band. The inner band, C, is smaller than the outer band, and is secured to its head D by means

of similar straps, which engage with the ring 55 which divides the two series of holes in the head in the same manner as above described. The two bands are now respectively secured each to its own head without soldering. The smaller band is now inserted within the larger 60 one, and, both being of the same length, the device will be presented as consisting of two cylinders with open heads so arranged that there will be an air-space between them communicating at each end with the outer air 65 through the outer series of holes in the heads. When in position as last described, it becomes necessary to fasten the two sections together. This I do by securing one or more leaf-springs e to the inner wall of the outer 70 band, so that they project beyond its end sufficiently far to engage with the outer ring of the opposite head through the holes therein. By this or equivalent means I am able to so connect the two sections together that 75 they may be separated at pleasure when it is desired to clean the inside of the bands from the accumulated dust. The inner series of holes, which may be partially broken out, if desired, allow communication with the outside air with the air-space surrounding the stove-pipe and between it and the inner band, the walls of the inner series of holes forming 80 a rest to support the stove-pipe centrally in the device.

85 I am aware of the Patents Nos. 199,423 and 279,205, and make no claim to the construction shown therein as forming a part of my invention.

What I claim as my invention, and desire 90 to secure by Letters Patent, is—

1. The band B, having secured thereto the metal head A by means of the metallic loops c, which pass through holes in said head, and the free ends of which pass along the inner 95 and outer wall of said band and are secured thereto by rivets, substantially as described.

2. A stove-pipe thimble consisting of two independent sections each of which is composed of a band and cast-metal head, the outer 100 of such bands being provided with springs riveted to its walls, and adapted to engage with holes in the head of the smaller band, substantially as set forth.

JAMES L. WILBER.
